Primary Examiner — Elizabeth J Oswecki(74) *Attorney, Agent, or Firm* — Venjuris, P.C.; Joseph R. Meaney(57) **CLAIM**

The design for a Christmas tree ornament, as shown and described.

DESCRIPTION

FIG. 1 is a top front perspective view of a Christmas tree ornament showing my new design;

FIG. 2 is a side view thereof;

FIG. 3 is another side view thereof;

FIG. 4 is another side view thereof; and,

FIG. 5 is a top view thereof.

The broken lines shown in the drawings represent portions of the Christmas tree ornament that form no part of the claimed design.

All surfaces not shown form no part of the claimed design.
